UNITED STATES PATENT OFFICE

157,822

BICYCLE WHEEL HUB ORNAMENT

Arthur D. Wolfe, Bellevue, Ohio, assignor to
The Bellevue Manufacturing Company

Application June 24, 1949, Serial No. 3,500

Term of patent 3½ years

(CL. D90—12)

To all whom it may concern:

Be it known that I, Arthur D. Wolfe, a citizen of the United States, residing in Bellevue, in the county of Huron, State of Ohio, have invented a new, original, and ornamental Design for a Bicycle Wheel Hub Ornament, of which the following is a specification, reference being had to the accompanying drawings, forming a part thereof.

Fig. 1 is a side elevational view of a bicycle wheel hub ornament showing my new design;

Fig. 2 is an end elevational view thereof; and

Fig. 3 is a perspective view.

I claim:

The ornamental design for a bicycle wheel hub ornament, substantially as shown.

ARTHUR D. WOLFE.
